Atty.

UNITED STATES PATENT OFFICE.

LELAN A. DAVIS, OF NEWARK, MARYLAND.

DOOR-CHECK.

SPECIFICATION forming part of Letters Patent No. 294,972, dated March 11, 1884.

Application filed December 8, 1883. (No model.)

To all whom it may concern:

Be it known that I, LELAN A. DAVIS, a citizen of the United States of America, residing at Newark, in the county of Worcester and State of Maryland, have invented certain new and useful Improvements in Door Stops and Holders; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to certain new and useful improvements in door-holders, its object being to provide a means whereby the attachment for the base-board may be adjusted so as to provide a catch for retaining the latch secured to the door; and my invention consists in the construction and combination of the parts, as will be hereinafter specifically set forth and claimed.

In the annexed drawings, which illustrate my invention, Figure 1 is a perspective view, showing the same applied. Fig. 2 is a plan view of the retaining-catch, which is attached to the base-board; and Fig. 3 is a sectional view of the latch attached to the door.

A represents a door, which is hinged in the usual manner; and B, the base-board to which the door-stop is usually attached, so as to project outwardly therefrom, so that the door will abut upon the stop and prevent the knob from injuring the wainscoting or wall. To the lower portion of the door, on a line vertically with the knob-spindle, is secured what I term a "latch," C, which latch consists of the portion a, which is provided with outwardly-projecting side wings and a retaining-screw, a', for attaching the same to the door, these parts being formed of a single casting. The side wings are perforated for the reception of a transverse pin, by means of which the latch C is held between the outwardly-projecting wings. Before attaching this portion to the door, I place over the screw a' a rectangular piece of leather, rubber cloth, or other flexible material, which will extend downwardly under the casting, and which is held in place by the screw a', which passes through the same. The latch C is provided on its lower side with

a lug, c, which will abut against the vertical portion of the casting, between the side wings, so as to prevent the latch falling below the parts by means of which it is attached to the door. Above the hooked portion of the catch I provide an enlarged head, which will serve as a weight and will hold the hook downwardly. This enlarged catch is provided with means whereby a cord can be attached to the same, which cord is indicated by the letter d, and extends from the latch to the spindle of the door-knob, to which it is attached, so that by turning the door-knob the cord will be tightened and the latch be raised, thus providing a convenient means for releasing the door when the same is held open by the latch. Attached to the base-board is a casting, D, which consists of a rectangular portion, d', which is provided with lugs or projections d', and a central perforation, through which passes an ordinary wood-screw for holding the same in position. This casting is provided on its upper and lower sides with two outwardly-projecting portions, e e, which, when the parts are placed in position, are horizontal or parallel with the floor. These outwardly-projecting portions e e are curved, as shown, and are provided with serrated edges, and centrally with a perforation, e', through which passes a pin, for the purpose of retaining the adjustable catch E thereto. This catch is provided at its rear portion with a vertical perforation, through which will pass the retaining-pin. The portion E is provided with vertical projecting lugs f, which will lie within the serrated edges of the horizontal portion of the casting. By means of these serrated edges and the projecting pin upon the catch, the catch may be adjusted at different angles, and though the door-frame may be at different angles from the base-board, the parts may be adjusted so that the catch and latch will coincide with each other when the door is opened. The outer end of the portion E is provided with an outwardly-projecting portion, g, which will abut against the door under the casting a, and upon the flexible cushions provided at this point.

By the arrangement and construction of the parts of my invention it will be seen that I provide a door holder and stop which are cheap in construction and effective in opera-

construction, and which may be furnished to the trade at a comparatively small cost, the same being applicable to doors and base-boards, and which may be readily adjusted and applied, so as to retain the door in position without regard as to whether the base-board is on the same line as the door-frame or at right angles or any other position therefrom.

Having thus described my invention, what I claim as new, and desire to secure by Letters Patent, is—

1. In combination with the latch C, pivoted between the vertical side wings of a casting, a rod for operating the same from the door-knob, a retaining-catch, E, with a cushioned end, g, pivoted

between projecting wings e e, with serrated edges for the reception of projecting pins f f upon the catch, substantially as shown, and for the purposes set forth.

2. The casting D, provided with horizontally-extending side wings with serrated edges, and an adjustable catch, E, having projecting pins f f, in combination with the pivoted latch C, the parts being organized substantially as shown.

In testimony whereof I affix my signature in presence of two witnesses.

LELAN A. DAVIS.

Witnesses:

ELIJAH B. CAREY,

HUGH J. KING.
